UNITED STATES PATENT OFFICE

2,059,222

TELEVISION APPARATUS

Reginald A. Fessenden, Chestnut Hill, Mass.;
 Helen M. Fessenden, executrix of the estate of
 said Reginald A. Fessenden, deceased

Original application January 14, 1927, Serial No.
 161,159. Divided and this application April 4,
 1928, Serial No. 267,373

12 Claims. (Cl. 178—6)

My invention relates to the transmission of energy, and still more particularly of signals and pictures and moving pictures, by high frequency impulses, and more particularly by high frequency currents, and still more particularly by Hertzian waves; and to the elimination of the disturbing effect of atmospheric and other injurious influences; and to the reduction of the cost and uncertainty of transmission.

10 This application is a division of my application Serial No. 161,159, filed January 14, 1927, which application is a continuation in part of my Patent No. 1,617,241, granted February 18, 1927.

It has for its object the accomplishment of such of the subjects to which it relates which have not heretofore been accomplished; and increased efficiency and simplicity and reliability and economy in such as have been accomplished.

It is a further development along the lines disclosed by applicant in his article in the Electrical World of Sept. 15th, 1894, (relating to "wired wireless" and the use of sine waves for "wired wireless", and the method transmitting signals in "wired wireless" by modulation instead of by opening and closing the circuit). And in the official experimental records of the U. S. Weather Bureau for 1900-1901; U. S. Patents 706,737, May 29th, 1901; 706,742, June 6th, 1902; 706,747, Sept. 23th, 1901; 1,015,881, Dec. 19th, 1906; U. S. patent application 222,301, Aug. 26th, 1904; (these relating to the generation and modulation of sustained electrical oscillations of Hertzian frequencies, and to broadcasting and transmission of pictures). And in other U. S. patents granted to, and articles written by applicant.

35 In the drawings accompanying this specification:

Figs. 1 and 2 show a transmitter and receiver for printed intelligence.

40 Figures 3 and 4 show, partly diagrammatically, the transmission and reception of intelligence; Figure 1 showing the sending end and Figure 2 the receiving end.

45 Figures 5 and 6 show a transmitter and receiver for a continuously moving intelligence carrier.

Figure 7 shows a light source and Figure 8 a light valve which may be used at the receiving station.

50 Figure 9 shows a scanning device for the transmission of colored pictures.

Figure 10 shows various forms of printing devices for printing characters on a tape.

55 Figure 11 shows a device for reproducing invisible images.

Figure 12 shows a device utilized in the transmission of colored images.

In Figure 1, 45 and 46 are rotating mirrors preferably of stellite though magnalium or silvered glass may be used, the axis of 45 being in the plane of the paper and the axis of 46 perpendicular thereto. These mirrors are driven respectively by the motors 47 and 48 whose speed is maintained uniform in any suitable manner, as for example by the method shown in Figure 1 of the applicant's U. S. Patent No. 918,303, April 13, 1907, or a single motor may be used and the two axes geared together as shown in the applicant's companion application Serial No. 161,159. The two mirrors form a sort of a rotating electrostat, and if the plane of the field of view to be transmitted be taken as perpendicular to the paper, then the rotation of 46 will throw on the light or heat actuated cell 50 (for the apparatus is capable of transmitting heat pictures as well as light pictures and so detecting battleships, aeroplanes, motors etc. and at night and in fog) a succession of small areas along the line that is to be scanned.

In the present arrangement shown in Figure 1 the element to be scanned comprises a band or tape 136 which has preferably a typewritten message impressed upon it by the typewriter 130, Fig. 1. The band may be stationary, as in Fig. 1, or continuously moved, as in Fig. 1, by means of the motor 49 shown at the right of the band, which motor carries a roller 48 upon which the band may be wound. Sufficient slack may be provided at the left end of the band before the position of the scanning so that impressing of the typewriter message upon the band may not interfere with the continued slow movement of the band itself. The typewriter, traveling band and motor are shown for the purposes of the drawings in the plane of the paper. For actual operation, however, it would be preferable to have the band traveling in a plane perpendicular to the plane of the paper so that the scanning may be made directly without the use of any converting mirrors.

Assuming that the band 136 in Fig. 1 is perpendicular to the plane of the paper and that the mirror 45 is rotated, then strips of areas will be taken from different heights in the field and successive strips will cover the whole field. If the band 136 were to be moved very rapidly, the mirror 46 is omitted since under such conditions a single element could be obtained for each movement of the mirror. This is shown in Fig. 1 where the frame 280 on which the message of

20

25

30

35

40

45

50

55

facsimile is produced is transmitted to the rotating prism 291 from which it may be reflected through a pin-hole opening 292 in the mask 293 to the light valve 53 through which the impulses 5 are impressed upon the transmitting circuit. The faces of the reflecting mirror 291 may be so tilted at different angles with one another that each mirror will consecutively scan the next line in the frame, the frame itself moving and 10 advancing to the position where successive lines are in position for scanning.

In Fig. 2 the receiving end is indicated corresponding to the sending end in Fig. 1. Here the beam 284 is reflected by means of a reflecting 15 surface 285 to the prismatic mirror 286 which rotates in synchronism with the mirror 291 and which casts the reflection of the beam on to the moving frame 287 operated through the motor 82' which should be in synchronism with 20 the motor 49.

When both mirrors are rotating simultaneously these strips of areas will be inclined to the horizontal at an angle depending upon the relative speeds of the mirrors and if it is desired to maintain them approximately horizontal, one of the 25 mirrors, for example 45, may be rotated many times faster than the other 48; and preferably an even number of times, which may be accomplished by so designing the gearing or the pole 30 numbers of the driving motors, or to produce slow beats between approximately equal speeds as described below.

In place of using flat mirrors, as shown in Figs. 1 and 2, prismatic mirrors with six or more sides 35 may be used, as shown in Fig. 3. By using these, when one end of a strip of areas is passing off from the light actuated cell 50, from one set or pair of mirrors, the beginning of another strip of areas can be made to be just beginning on 40 another pair of mirror surfaces.

The angle of the field of view to be transmitted will depend upon the distance apart of the mirrors and their size, and this can be calculated in advance by optical methods, or determined 45 experimentally. The optical system 53 and 53' may be used for making more areas at center of field or object of most interest and thereby give greater brilliancy or definition, this being reproduced at receiving end.

50 The mirrors may be ground to spherical or cylindrical faces, but are preferably flat and what focussing etc. is desired is preferably done by the optical system 53 and 53'. In addition to the matter of convenience, the lens 53 may be made 55 of substances more or less opaque to heat rays, and may be built up of parts 52 and 54 so as to let through a spectrum distribution corresponding to that of the eye, by using differently tinted glasses. Or it may be made very trans- 60 parent to heat waves, as when the apparatus is used on board an aeroplane at night time or in a fog, to show the pilot the configuration of the ground by a thermal view, transmitted into a visual one.

65 The light responsive cell 50, which I call the photocrat, because it governs the transmission of energy in accordance with the light received on it, (from the Greek words meaning "light governor") may be of any suitable type, for example a hot wire barretter, as here indicated, comprising a vacuum tube 55 in which are provided two supporting conducting elements 56 and 57 which feed current to the small hot wire element 58 or which react through the light 70 thrown on the wire element to produce a cur-

rent in the connecting leads 56 and 57 for modulating the transmission circuit as will be explained presently. This device as shown in applicant's U. S. Patent 706,744, June 3th, 1902. The wire is preferably straight, and of gold, 5 blackened, and one ten-thousandths of an inch in diameter, wire of this size having been drawn by me and found suitable and reliable. It is connected up in any suitable way, for example as shown in applicant's U. S. Patent 706,742, Fig. 1, 10 except that the terminals of the barretter are not connected directly to the antenna, but to an amplifier or transmission circuit, which the barretter modulates, and the telephone 15 is omitted.

The cell 50 may be initially energized by means 15 of the battery 59 through a drop wire 60, the choke coils 61 and 62 being used to provide a high impedance to the variations caused by the radiant energy impressed upon the cell element 58. The cell element 58 is connected through 20 the conductors 56 and 57 and the external wires 63 and 64 to an amplifier 65 which may be connected to a transmission circuit or as indicated in the drawing to a radio transmitter 66 for impressing the impulses in a suitable manner on 25 the antenna 67. The amount of local current from the battery 59 which may be used to increase the sensitiveness of the cell element 58 is adjusted by means of a drop wire 60 usually to about one milliampere, the best current for 30 varying conditions must be found by trial and adjustment. As indicated the cell is enclosed in a vacuum by means of a container 55 and this has proved to be preferable under most conditions, but it is not however necessary under all 35 conditions to keep the cell so enclosed as it may be surrounded by other means that are heat opaque or visually transparent to different spectral characteristics.

A multiple barretter, as shown in Fig. 4, may 40 be used in place of a single wire.

When a linear receiver, as a single barretter wire is used, the lens 52 is preferably of the cylindrical or cylindro-spherical type, so as to concentrate the image of the small picture area falling on it into a line which shall fall on the fine wire, and so no picture radiation be wasted.

When it is desired to transmit the picture in its natural colors, successive faces of the prismatic mirror 54, Fig. 3, may be coated with this film so 50 as to reflect red, yellow and blue, as shown. Or different heights of the cylindrical lens 52 may be made of suitable absorbent material, and the faces of 54 ground so that successive faces fall on different parts of the lens, thereby successively transmitting red, blue and yellow light of suitable spectrum composition to the photocrat.

A further modification of this is illustrated in Figure 6. In this figure 1 shows a screen to be viewed, and 16 a prismatic mirror having six or 60 more faces with surfaces coated properly so as to reflect, red, orange, yellow, green, blue and violet, as indicated by the respective letters, R, O, Y, G, B and V. The prismatic mirror may be rotated on the shaft 2 by means of the motor 3 at any desired speed and the image from the prismatic surfaces may be reflected on the lens 13 which may be cylindrical or any other useful type. The lens 18 may be arranged with sections, a, b, c, d, e, f, for passing or reflecting the corresponding lights 70 from the respective mirrors, R corresponding to a, V to b, B to c, G to d, Y to e, O to f.

In place of using a hot wire barretter, or applicant's thermophone (see applicant's article in the London Electrician, June 24th, 1904) or a sensi- 75

tive thermocouple, (see same article,) a light sensitive vacuum tube may be used, as shown in applicant's patent U. S. 1,133,435, Feb. 9th, 1914. Or an alkaline metal amalgam vacuum cell. Or 5 a selenium cell, suitably shunted to give rapid response. Or a polarizing cell of the Minchin or other suitable type. Or a gas expansion cell, actuating a telephone diaphragm. Amongst other new devices for this purpose, applicant has 10 covered that substantially all transparent bodies have their specific inductive capacities changed when light of the wave-length which they absorb falls on them. This is especially marked in the case of strongly fluorescent bodies. The effect is 15 small, but is readily amplified, and condensers so made will themselves act as amplifiers if a high frequency current be impressed on them. As a rule the response is rapid enough, but where it is not, the substance may be made to rotate or flow 20 rapidly between the plates of the condenser. Substances of different spectral absorptions may be used, and so chosen as to have any desired spectrum characteristic, and in the case of fluids, may be dissolved in one another. This variation 25 of specific inductive capacity may be used to modulate the transmission circuit, in manners obvious to those skilled in the art, see U. S. Patent 706,747 of applicant.

In operation, therefore, as each small picture 30 area is reflected and focussed upon the photocrat, the photocrat generates an electric impulse proportional to the amount of light or heat falling on it, i. e. as emanated from the original small picture area. This minute electric impulse, with 35 or without amplification, actuates the amplifier 65 of the transmission line or the radio transmitter 66, which latter may be any circuit suitable for the transmission.

Where the transmission is by wire lines, or other 40 conductors, the generator of the transmitting station may be omitted, and the modulating impulses, preferably amplified, may be used for the reproduction.

This succession of small picture areas therefore, 45 sweeping over the photocrat, modulates the transmitted current or radiation in accordance with the luminosity, or temperature, or luminosity and color, of said picture areas.

This modulated current is received at the reproducing station, and there employed to reproduce 50 the picture, or the scene which is going on, at the sending end, for example a photograph, or a baseball game, or a scene from an opera.

Even with the somewhat crude apparatus, and 55 insufficient amplification employed by applicant, applicant has succeeded in cutting down the time of modulation and reproduction of a transmitted image per single image area to one fifty-thousandth of a second. Allowing five repetitions per 60 second for persistence of vision, it will be seen that this gives 10,000 (ten thousand) small picture areas for the field of the picture, or, allowing fifty areas per linear inch, at ten inches focus, (the usual process print definition,) this gives a 65 picture ten feet square on the movie screen at the reproducing end, at a distance of fifty feet, which is sufficient for substantially all practical purposes. And applicant's tests have shown that with increased amplification and with more care- 70 fully constructed apparatus, there is no difficulty in obtaining 250,000 picture areas per second, with a corresponding increase in reproduced image area.

It will be noted that the smallest object which 75 can be seen by the human eye subtends an angle

of one minute of arc, which at the normal focal distance of ten inches, is 1/300 inch diameter, and that this is in a stationary field and not a moving one, and with perfect contrast. In process prints, where the field is fixed but the contrast is not perfect, as it is in a line drawing in black and white, areas as large as 1/50 inch in diameter are found to give very satisfactory results. Where the picture is a moving one, even larger areas are found satisfactory.

In addition, with applicant's arrangement the definition is very much improved over the process print for the reason that while the invention may be used to transmit and reproduce a succession of discontinuous picture areas, or dots of varying 15 darkness, as described in applicant's U. S. Patent 1,015,881, Dec. 19, 1906, but by means of a different invention, yet it may be, and as shown is preferably used to transmit by continuously modulating the transmitting impulses. This continuous modulation of the transmitted impulses in accordance with the varying intensities of successive small picture areas gives much more satisfactory optical effect.

In Fig. 2 the projector 77-81 is preferably a 25 continuous current arc lamp projector or a point-light projector with a source as indicated by 78 in Fig. 2. I have found that an alternating current does not give good results except when used 30 with a tungsten or similar type of incandescent lamp, and at high frequencies of the order of 10,000 per second or more.

The device 76 for modulating the projected light in accordance with the received modulated impulses is shown in detail in Fig. 4. It consists 35 of a form of shutter which applicant has tested up to speeds of 1/200,000 (one two hundred thousandth) of a second, using only a few micro-amperes of current. This shutter, which I call the cratophote since it governs the light, whereas 40 the photocrat is light governed, is based on applicant's filament galvanometer, described before the Indiana Academy of Sciences in 1892, and is related to those forms shown in applicant's U. S. Patents 1,172,018, March 14th, 1908, Figs. 2, 3 45 and 4; 1,045,732, June 16th, 1908; 979,145, Dec. 23rd, 1907; and 706,737, May 29th, 1901.

As shown in Fig. 4, and in applicant's Patent No. 1,617,241, and in U. S. Patent 1,172,018 in part, two rows of fine wires 71 and 72 are placed 50 with the spaces between the wires of one row opposite to the wires of the other row, so that when placed in the path of the projector beam no light, or only a predetermined amount, can pass through, the grids or wires 71 and 72 being 55 placed in the magnetic field of the coil 74, (a permanent magnetic field may be used if desired,) so that when a current is passed through the wires of the grids, the wires of each grid will move in opposite directions and let the light through. 60 If this current is the light modulated current from the transmitting station the amount of light let through will correspond to the illumination of the succession of small picture areas at the transmitting or observing station.

A predetermined amount of light may be allowed to pass through the shutter in the absence of, or independent of, the modulating current, by passing an auxiliary direct current through the 70 wires of the grids; and by adjusting the current as shown in the magnetizing coil 74; and by tilting the grids sideways to each other.

When the light from the projector strikes the grids, the wires expand, and to take the slack out 75

of the wires, an additional magnetic field, generated by the coils 75, 76 is used, which tightens the wires without disturbing their alignment; in fact making it more stable.

5 The wires may be of any suitable size. Applicant has used wires as small as 1/10,000 inch and as large as 1/1,000 in. They can be left bright or lightly silver plated and dipped in sodium sulphite to blacken them, after mounting. I prefer 10 to draw the wire with the silver sheath half the thickness of the gold core, wind the wire on two grid frames placed back to back, with the silver sheaths touching, solder the wires, or spot weld them, to the frames, cut the two frames apart, 15 and dissolve the wire sheaths with the apparatus shown in applicant's paper on "Wireless Telephony", (transactions of the American Institute of Electrical Engineers, July 1908).

The wires 71 and 72 may be held by a frame 20 73 and may be connected to a radio receiver 69 so that the impulses received from the antenna 68 may be impressed through the receiver directly upon the light modulating device. It should also be noted that the projector 77 may be provided 25 with suitable lenses 79 and 80 for concentrating the light either in a point or line source dependent upon the position and shape of the shutter 70.

As indicated in Figure 2 a second lens 81 may be used in the system and positioned beyond the 30 shutter 70 to provide the proper light beam for ultimate reflection upon the projecting screen 82 or moving tape as indicated in Figure 2 by means of the mirror system including the mirrors 83 and 84 operated respectively by means of the motors 85 and 86. A further lens 87 may be provided 35 for concentrating the light in a suitable manner just before projection on the screen 82. The motor 82' may cause the tape or screen to travel in corresponding synchronism with the motor 49 40 at the sending end.

In order to utilize fully the shutter and to heat all wires uniformly, the projector 77 may be fitted with cylindrical, in addition to spherical, lenses, and a cross cylindrical or other suitable combination of cylindrical and spherical lenses used to 45 reform the image, if desired, after the beam has passed through the shutter.

As the grids act to some extent as a spectroscope and give rise to other diffraction phenomena, they are made adjustable as to distance by means of wedges, the distance being varied till the operation is most satisfactory. It will be found that by proper adjustment the efficiency 50 of the shutter may be made several times greater than that corresponding to the size of the wires used. The usual heat screen may be used between projector and shutter, and the grids may be in hydrogen or vacuum.

While this form of cratophote has been found 60 suitable, other forms may be used, for example the devices shown in applicant's U. S. Patents 1,044,637, July 14th, 1905; and 1,045,781, June 16th, 1908. For example, Fig. 3 of the former may be actuated by the modulating current to 65 move a grid of wires, or a piece of glass or mica having alternate transparent and opaque portions, or to rotate a mirror and so throw the projector light away from or through the opening through which the light passes to the screen; and 70 this opening may itself be fitted with a grid and the mirror may have the silvering or platinizing in strips, like a grid, so that a very small motion of the mirror about its axis will throw the light through the opening to the screen, or shut it off.

75 Or, as shown in applicant's U. S. Patent 915,280

Feb. 8th, 1907, the intensity of the light source itself may be varied by the received current and so modulate the light thrown on the screen. Fig. 4 shows the method applied to a pointolight lamp, 20 being the coated electrode of the arc, 21 5 the incandescent tungsten bead, and 22 and 23 the modulating electrode modulated by the modulator 24, the electrodes 22 and 23 arranged inside the tube 26, as in DeForest's invention of the audion in connection with the Edison valve, 10 (Edison U. S. Patent 307,631, Oct. 21st, 1884) instead of outside, as in applicant's Patent 915,280. Illumination in the tube may be provided through the potential 25. Other methods will suggest themselves to those skilled in the art. 15

The grating shutter type of cratophote has certain advantages; for example it is so sensitive that it may be used, where the movie screen is small and mounted on the arm of a chair or a desk, without amplification at the receiving end, 20 and also without the use of a carrier current in the transmission line or wireless antenna. A few microamperes of current are sufficient to operate it. It operates very reliably up to frequencies of alternation of 200,000 per second, and without doubt up to 1,000,000 per second, though 200,000 per second is all that applicant has actually used to date. It is easily adjusted electrically, so as to let any predetermined amount of light through in the absence of the modulating 25 current. All natural period of vibration may be eliminated by the method shown in applicant's U. S. Patent 1,319,521, June 8th, 1917. The range and overload capacity are much greater than any other known instrument, as with wire of gold 30 and 1/10,000 inch diameter an indication is produced with 1/1,000,000 ampere of current, but it will carry 1/1,000 ampere safely, i. e. a ratio of 1 to 100,000 in current or 1 to 10,000,000,000 in energy. It also lends itself readily to mechanical 40 and electrical heterodyning, the advantage of which is more fully explained in another application.

A further important advantage of this form of shutter, when used in this connection, is the 45 fact that the light transmitted through the shutter is a multiple valued function of the current; for as the current increases the wires of the two grids are brought in line, one behind the other, and the light passed is then a maximum. If the 50 current be still further increased, the wires begin to pass each other, shutting off the light, more and more, until the wires of one grid are now opposite the spaces of the other grid, and the light is a minimum. If the current be still further increased, the light passed increases again, and reaches a second maximum, and so on. This 55 multiple valued relation of impulse to effect has the very important and hitherto unsuspected property that it greatly diminishes, in fact practically eliminates, all injurious effects of atmospheric and other disturbing impulses in transmitting pictures, and signals, of all kinds. For if, in projecting a radio-movie of a distant scene, 60 a strong atmospheric impulse occurs, there will be no intensely bright flash of light on the screen to disturb the eye and spoil the rest of the picture by irradiation, after effect and the like. But on the contrary, it will be as apt to reduce the 65 intensity of the luminosity of the small picture area affected as to increase it, i. e., the result will be a grey unit area instead of at worst a white or dark area, and there will be no injurious irradiation or after effect etc. And similarly for 70 75

other types of signals, for example, telegraphic signals.

Where alternating currents or Hertzian waves are used for carrier currents, a rectifier may 5 be operatively connected to the shutter, as shown in applicant's U. S. application Serial No. 286,914, filed Nov. 11th, 1905; and applicant's U. S. Patent 222,229, Aug. 26th, 1904, Fig. 2, divided from U. S. Patent 222,301, filed Aug. 26th, 1904; and 10 well known in the art.

After passing through the optical element 81 above described, the modulated light is received on the mirrors 84, 83, which are of similar construction, and operated similarly to the mirrors 15 45, 46. By them the picture elements are distributed on the screen 82. The reproduction process, it will be seen, is substantially a reproduction of what takes place at the sending end, with action reversed.

20 These pairs of constantly revolving mirrors, on axes, constantly shifting in phase, and inter-reflecting, I call for convenience "heliopes", a term used by Homer to express the rapid rolling of eyes in all directions, and somewhat euphemistically translated as "quickly glancing". Both heliopes, i. e., the one at the sending station and the one at the reproducing end, are preferably driven at constant but adjustable speed, as stated in describing the set 43, 46. The relative speeds 25 of each mirror of a heliope, say 45 and 46, are so adjusted that each picture area will recur sufficiently often to give the required persistence of vision, for example $\frac{1}{5}$ second apart. This may be varied either by varying the speed of the 30 whole heliope, or by varying the relative speeds, and the definition may be varied similarly. This recurrence may be effected by, amongst other ways, making one mirror turn only five times per second, and the other turn 5,000 or 50,000 35 per second, or in the case of a 25 sided mirror, in 5 seconds and one two thousandth of a second.

But it is preferred to so gear the mirrors together that one makes 5 turns more per second than the other, for example 45 makes five turns 40 more than 46, and similarly for 84, 83.

The regulation of the heliopes need not be automatic. It has been found in practice that if the speed be wrong a distorted blur is seen, but that by changing the speed of the heliope 45 50 84, 83 it gradually straightens out, becomes intelligible and erect. The mirrors are, however, preferably fitted with fly-wheels or the equivalent.

55 Pictures or messages may be sent in undecipherable code by tilting successive sides of the rotating mirrors so as to make the picture area strips succeed each other at arbitrarily determined order, both horizontally and vertically. The chances of any one not knowing the exact 60 angle for each mirror side detecting the message would be one in many millions. This method may be used for cypher purposes generally, and the message may be photographed. Even if an operator "seeing in" managed to strike the right 65 speed of mirror 45, and the right ratio of speed of mirror 46, nevertheless what would appear on his mirror as two adjacent strips of mirror images would really be two non-adjacent complex curve strips of the picture actually sent, and so 70 the reproduction made by the "seer-in" would be a crazy patch quilt.

The gearing of the two mirrors 45, 46 need not be continuous, i. e. instead of rotating at a constant ratio of speeds they may rotate continuously at the same, or some multiple of each

other's speed for one-fifth of a second; then by dropping a tooth of the gear, or the equivalent device, one may lose a single or other fixed number of turns to the other.

5 In place of mounting the mirrors 45, 46 (or 84, 83) on different shafts greater accuracy of conjoint movement may be obtained by mounting them on the same shaft, one mirror, say 45, being fixed rigidly to the shaft, and the other 46, revolvable about the shaft, and a gearing driving 10 46 around slowly relatively to 45. For example, if the carrier frequency is 1,000,000, and the picture element area frequency is 200,000, and the picture recurrence frequency is 5; if the mirrors 45, 46 are twenty sided, then the shaft and mirror 15 45 will revolve 3,000 times per minute; and mirror 45, if it were rigidly attached to the shaft, would also rotate 3,000 times per minute, but it is slowly driven by the gear relatively to 45, and so only rotates 2,700 times per minute.

20 A fixed mirror system is used in this case to make the necessary change of reflecting angle between the two mirrors 45, 46, and this allows of the construction of a view finder, by taking a small amount of the light which would fall on 25 the photocat, or the equivalent falling on another point, and reflecting it back on the heliope, and thence on a ground glass or other screen.

In place of, or in addition to, the regulator referred to above, as described in applicant's paper 30 on wireless telephony, in the transactions of the American Institute of Electrical Engineers for July 1908, the "fly-wheel circuit" described in applicant's U. S. application Serial No. 222,301, filed Aug. 26th, 1904. This should be connected 35 to the A. C. regulating motor, and should be resonant to the motor frequency, and have as large capacity as possible and minimum dielectric losses. The capacity or inductance should have a very fine adjustment, so that the resonant frequency can be slightly varied. Fig. 5 shows the use of the invention for telegraphing and working 40 multiplex on a single frequency, and eliminating atmospheric disturbances, and thereby reducing the size and cost of stations. Any suitable means of sending may be used, but it is preferred to use typewriters 130, 131, 132, which type 45 the messages, thus giving a record at the sending end. To transmit a line or any convenient short portion of the message is exposed to the heliope. 50 The line exposed may be a line of the actually typed message, as 136. Or the typewriter may be of the standard Morse sender type, which sends a Morse signal each time a key is struck, corresponding to the letter typed on the paper, and 55 this signal may be used to operate trip switches on a travelling band of incandescent lamps, a dot lighting one or two lamps, as indicated at 133, and a dash lighting two or four lamps, as indicated at 133', the trip switches being opened by 60 another trip as the lights on the band pass back of the pulleys, or outside of the field of the heliope; as shown at 135. Or the typewriter may set up the actual letters 134 in incandescent 65 lamps, on the travelling band of incandescent lamps, as with the Mergenthaler type setter, as shown in the band 134'.

In each case the message is exposed to the heliope and transmitted as above described in the case of the picture, and reproduced at the 70 receiving end where it is thrown on a screen and a corresponding number of typists take the message down, each typist typing down the words which appear on the line which is allotted to him. If desired the lines may be of different 75

colors, as explained in connection with the transmission of colored pictures. Or, by an optical arrangement of mirrors, each line may be made visible to the typist concerned, and 5 to no other, each line being reflected to a different position.

This method has the advantage that a considerable number of messages may be sent on the same wave length, and received at different 10 stations. For example, New York may send 12 messages, of which four may be received at London, two at Rome, three at San Francisco, one at Rio Janeiro, and two at Warsaw. Or six 15 messages may be sent out from New York to 15 different stations, and simultaneously six may be received from other stations, or the same stations, New York sending on the 1st, 3d, 5th, 7th, 9th, and 11th lines of the pictured message, and receiving on the other lines; and the same 20 heliopes may be used for both sending and receiving, the reproduction screens being semi-transparent and the travelling incandescent lamp belts placed behind them, (or to one side if preferred,) and the impulse modulating cell, 25 or photocrat, placed to one side. In telegraphing by this method the receipt of the messages is not interfered with by atmospheric or similar disturbances. The receipt of a strong atmospheric discharge merely makes a grey dot, lasting 30 for a fifth of a second, on some part of some particular letter, and does not interfere in any way with the visibility of the whole word or letter. In other words, the effect of the atmospheric is distributed over the whole message. 35 Or, in other words, there is no one to one correspondence between the signal element and time; the time is a multiple valued function of the signal element, but ultimately a single valued function of space; and as the atmospheric dis- 40 turbance is a single valued function of time but a multiple valued function of space, its effect is substantially negligible so far as the signal is concerned.

This new method is not limited to optical 45 means. For example a mechanical equivalent to the heliope may be used, by using a Wheatstone tape, and passing it under a succession of brushes, making contact through the holes, or under hole operated relays, transmitting the im- 50 pulses as a multiple valued function of the time, and co-ordinating, at the receiving end, by a similar set of brushes, them into a single valued function of space; with or without the use of time lag devices at the receiving end, or of 55 synchronous commutators, and actuating the brushes at the receiving end in predetermined order.

Static being eliminated, it is possible to use 60 higher amplifications, and hence smaller antenna at the stations. Applicant prefers to use his loop antenna, or wireless pelorus, as described in German Patent 225,256, Jan. 14th, 1907; British Patents 4,710 and 28,412, 1907; U. S. Patent 754,058, March 8th, 1903 and U. S. 65 Patent 1,020,032, July 27th, 1903; and in the "Electrical World", Aug. 12th, 1899; and the London "Electrician," Dec. 19th, 1919.

Many modifications will suggest themselves to 70 those skilled in the art. For example, the heliope described above, in which both mirrors are mounted on the same shaft, one fixed and the other loosely, and the intermediate mirror system for changing the reflecting angle is fixed, may be modified by fixing both mirrors 75 firmly on the shaft, and mounting the intermediate

system loosely on the shaft, and revolving or oscillating slowly with respect thereto. And the mirrors themselves may oscillate instead of rotate. Many other uses will suggest themselves to those skilled in the art. The method of telegraphing so that no other station shall be able to receive the messages unless it has the information as to the tilting of the mirrors or sequence of the image areas has been described above in connection with the transmission of pictures. 10

The area of the picture may be increased by using higher frequencies of the carrier current, which is possible over long distances because the elimination of atmospheric makes greater amplification possible; also relay stations may be 15 used, as shown in applicant's U. S. Patent 974,763, Jan. 14, 1907, and acting as centres of news and picture distribution. A plurality of heliopes may be used to take and reproduce a single picture. 20

It may be used for meteorological purposes, to map out the advance of bodies of air of different temperatures. When used for detecting aeroplanes at night or in fog, a sight consisting of a circle of electrically heated wire may be 25 used, the image of which is thrown on the screen. Or two cross wires, heated as indicated in the arrangement shown in Fig. 8, may be used, showing by their rectilinearity the accuracy 30 of the synchronism; and the images of which may be used to automatically regulate the speed of the heliope and keep it in synchronism by actuating heat or light responsive cells when the image of the wires moves from its proper position. See applicant's U. S. Patent 979,145, Dec. 35 23, 1907.

In Figure 7 the view to be scanned is indicated at 27 and a scanning mirror at 28 driven by the motor 29 at a certain chosen speed. In conjunction with the scanning mirror there is 40 provided a frame 30 through which the rays from the object to be scanned pass to the scanning mirror. The frame is provided with cross wires 31 and 32 which may be heated from an external source 33 by means of the leads 34 and 45 35. In this way not only may a reference be obtained but it is also possible as mentioned above to use this arrangement in maintaining the synchronism between the sending and the receiving systems. 50

It may be used in conjunction with applicant's wireless telephone, U. S. Patent 706,747, Sept. 28th, 1901, and American Telephone Journal, Jan. 26th and Feb. 2nd, 1907, and Proceedings Amer. Inst. Elect. Eng. July 1908. In this manner talking movie pictures may be transmitted; it being preferred to use in this connection the arrangements shown in applicant's U. S. Patents 1,213,176, June 27th, 1917; and 1,277,562, Feb. 28th, 1917, and other U. S. applications of applicant. 55

Applicant has discovered, and claims the inventions, that both speech and pictures may be simultaneously transmitted on the same carrier frequency; or when a carrier current is not used, the speech can be transmitted on the same transmitting circuit as the pictures, the picture area frequency having been found by applicant to be as a rule so much higher than the speech frequency that there is no substantial interference. 70

The method may also be used for transmitting speech, with an acoustic heliope, the time being so made a multiple valued function of the sound element, and in this way the effect of disturbing noises eliminated. 75

While the grid galvanometer shown in applicant's U. S. Patent 1,172,018, March 14th, 1908, is not adapted for use as a wireless receiver, by reason of the wires being made resonant to a natural period, and the field being a continuous current one, and other reasons, and has not therefore been so used, the grid arrangement shown in Fig. 4 and herein claimed, is well adapted, as applicant has discovered, for this purpose. It is also well adapted for heterodyning, by passing a high frequency current through the magnetizing coil 74. This new type of grid galvanometer receiver has the great advantage that it substantially eliminates the effect of atmospheric, for the reasons mentioned above in connection with the effect of atmospheric disturbances on picture transmission; in contradistinction to the earlier type vibrating at a natural period, which gave the same type of indication on receipt of an atmospheric disturbance as on receipt of a signal, the present type, being dead beat, gives a small and easily distinguishable effect. It is not necessary that both sets of grid wires should move, or move in opposite directions when used for the method herein described.

Speech may also be transmitted by forming the picture screen at the sending end of a number of applicant's thermophones, (Electrician, London, June 24th, 1904), each tuned to a short range of voice frequencies as in applicant's U. S. application 35,957, Jan. 23rd, 1915, and actuated by the speaking voice as therein described, or by other suitable means, and after transmission reproducing the speech in reverse fashion, or its equivalent. The repetition frequency for this purpose should be much higher, as will be found experimentally.

The grid receiver shown in Fig. 4 is especially suited to transmit speech on account of its freedom from disturbance by atmospheric, when acting as a wireless receiver. The atmospheric can never reach above a certain intensity, and the speech is always superimposed upon this, and the change of phase or reversal of the speech frequencies, due to the phenomenon referred to in connection with the transmission of pictures, does not affect the speech appreciably.

When the grids 71, 72 are used with an electromagnetic field, especially a heterodyne field, it is preferred to divide each grid into two or more sections and cross connect them and balance them by shunts or otherwise. For example, if the wires of the left hand half of grid 71 move to the right, those of the right hand half should move to the left. Or both 71 and 72 should be wound together on a threaded support. If this is not done, fluctuations in the field will move the wires in the absence of signals. In use the field is adjusted until when the desired signals are being received the wires of the grid move approximately to the centre of the spaces obtaining when no signals are being received. In this position, the wires of the two grids are in line with each other, and the maximum amount of light or heat, approximately, passes through the grids and falls on the selenium cell or thermophone or equivalent device or screen. When adjusted for working the wires need not have the same positions they have when no current or field is on, but may be at any desired distance therefrom, preferably an even number of spacings, or wire diameters.

The effect of atmospheric or disturbing signals is, whether rectifier, or heterodyne, or plain receiver without either is used, (see applicant's U. S. application Ser. No. 461,752) to change the phase

of the received signal, and in some cases, to introduce a higher harmonic. A strong static discharge will make the wires of one grid pass by five or ten wires of the other grid, but no matter what their position they will operate to modulate the light or heat from the projector at the frequency of the signals, or a multiple thereof.

The light or heat projector may project several horse power, or even several hundred horsepower, and the grid arrangement acts as an amplifier, and also, by inserting a tuning circuit or its equivalent in the circuit, (or mechanical regulator,) as a generator of oscillations of any desired frequency, i. e., 1,000,000 or more, though 50,000 is the most applicant has had any object in generating by this means to date; the possible frequency being obviously much greater, especially when light or heat absorbing insulators are used as photocrats, as described above.

I claim:

1. In a transmitting system for transmitting intelligence, a device for mechanically printing characters on a tape member, means for feeding the tape from said device to a scanning member, means for scanning the tape member, means for converting the scanning results into electric currents and means for reproducing the record.

2. In a transmission system for transmitting intelligence, a device for mechanically printing characters on a tape member, means for feeding the tape from said device to a scanning member, means for scanning the tape member, means for converting the scanning results into electric currents, and means for modulating therewith a radio transmission circuit.

3. In a transmission system for transmitting intelligence, a device for mechanically printing characters on a tape member, means for feeding the tape from said device to a scanning member, means for scanning the tape member, means for converting the scanning results into electric currents, a radio transmission circuit and means for impressing said electric impulses thereon to vary the transmission thereof.

4. In a transmission system for transmitting intelligence, a typewriter, a tape for receiving printed characters from the typewriter thereon from the typewriter, means for feeding the tape from said device to a scanning member, means for scanning the tape member, means for converting the results into electric currents and means for impressing the same on a transmission circuit.

5. In a transmission system for transmitting intelligence, a typewriter, a tape for receiving printed characters from the typewriter thereon from the typewriter, means for feeding the tape from said device to a scanning member, means for scanning the tape member, and means for converting the scanning results into electric current.

6. In a transmission system for transmitting intelligence, a typewriter, a tape for receiving printed characters from the typewriter thereon from the typewriter, means for feeding the tape from said device to a scanning member, means for scanning the tape member, means for converting the results into electric currents, means for impressing the same on a transmission circuit, and means for reproducing the record.

7. A unitary system comprising a travelling tape, means for mechanically printing characters on the tape, means for feeding the tape from said device to a scanning member, means for causing a light beam to scan said tape after the record has been made, means for converting the scan-

- ning results into electric current and means for reproducing the record.
8. The method of transmitting wireless messages which comprises forming printed characters on a tape by the action of a typewriter scanning the tape, by causing a light beam to scan the same, converting the scanning results into electric impulses and reproducing the record.
9. In the art of detecting bodies by means of heat waves emanating therefrom, means for scanning an object to be observed, means responsive to the scanned heat waves for producing a picture of the object and local heat emanating means cooperating with the scanning means for fixing the position of the body.
10. In the art of detecting bodies by means of heat waves emanating therefrom, means for scanning an object to be observed, means responsive to the scanned heat waves for producing a picture of the object and local heat emanating

means comprising a reference wire adapted to be heated cooperating with the scanning means for fixing the position of the body.

11. In combination with a television transmitter in the art of transmitting color images or vision by electric impulses, a lens system having transverse sections of different absorbent material and a prismatic reflecting mirror of varied colored faces adapted to reflect successive faces on different sections of the lens.

12. In combination with a television transmitter in the art of transmitting color images or vision by electric impulses, a lens system having transverse sections of different absorbent material and a prismatic reflecting mirror of varied colored faces adapted to reflect successive faces on different sections of the lens and modulating means responsive to the radiations passed by said lens.

REGINALD A. FESSENDEN. 20
